Primary Examiner — T Chase Nelson*Assistant Examiner* — Kelly L Gross(74) *Attorney, Agent, or Firm* — Banner & Witcoff Ltd.(57) **CLAIM**

The ornamental design for a medical imaging device, as shown and described.

DESCRIPTION

FIG. 1 is a front elevational view of a medical imaging device showing our new design;
 FIG. 2 is a back elevational view thereof;
 FIG. 3 is a top plan view thereof;
 FIG. 4 is a bottom plan view thereof;
 FIG. 5 is a left-side elevational view thereof;
 FIG. 6 is a right-side elevational view thereof; and,
 FIG. 7 is a top, front, left-hand side perspective view thereof. The greyscale contrast represents a contrast in appearance only and does not represent any particular color, material, or texture. The broken lines immediately adjacent to the shaded areas define the bounds of the claimed design and form no part thereof. The broken lines within the shaded areas form no part of the claimed design. The broken lines depicting the remainder of the medical imaging device form no part of the claimed design.
